UNITED STATES PATENT OFFICE.

PETER IVARSEN NAMTVEDT, OF TERRIL, IOWA.

VEHICLE JACK.

Application filed February 14, 1922. Serial No. 536,584.

To all whom it may concern:

Be it known that I, PETER IVARSEN NAMTVEDT, a citizen of the United States, residing at Terril, in the county of Dickinson, State of Iowa, have invented a new and useful 5 Vehicle Jack; and I do hereby declare the following to be a full, clear, and exact description of the invention, such as will enable others skilled in the art to which it appertains to make and use the same.

The invention relates to vehicle jacks, and has for its object to provide a device of this character comprising a bifurcated standard, a lever pivotally mounted in the bifurcation 15 of said standard and provided with link mechanism having a parallel movement and lazy tong movement, and adapted to engage an axle and force the same upwardly upon a downward movement of one end of the 20 lever. Also to provide a pivoted spring actuated dog adapted to cooperate with a notch in the standard for holding the device in extended position and the axle in raised position.

25 A further object is to provide a pivoted weight member cooperating with a spring for releasing the detent against the action of its spring when it is desired to lower the device and the axle supported thereon.

30 With the above and other objects in view the invention resides in the combination and arrangement of parts as hereinafter set forth. 35 shown in the drawings, described and claimed, it being understood that changes in the precise embodiment of the invention may be made within the scope of what is claimed without departing from the spirit of the invention.

In the drawing:

40 Figure 1 is a side elevation of the jack, showing the same in extended position.

Figure 2 is a rear elevation of the jack.

Figure 3 is a horizontal sectional view through the standard taken on line 3—3 of

45 Figure 1.

Referring to the drawing, the numeral 1 designates the base of the jack, and 2 an upwardly extending sleeve carried thereby and provided with a rectangular shaped chamber 3. Slidably mounted and vertically movable 50 in the chamber 3 is the lower rectangular shaped portion 4 of the standard 5. The standard 5 is held in various positions by means of the nose 6 of the detent 7 cooperat- 55 ing with any of the notches 8 in the portion 4 of the standard. The detent 7 is provided

with a substantially horizontally disposed arm 9 adapted to be engaged by the foot of the operator for rocking the lever detent 7 on its pivotal point 10 against the action of the spring 11, thereby allowing the standard 5 to be lowered to any desired position according to the type of vehicle being raised.

Pivottally mounted in the bifurcation 12 of the standard 5 on the bolt 13 is an angularly shaped operating lever 14, the arm 15 of which extends outwardly and is provided with a chamber 16 for the reception of an extension, if so desired. Pivoted at 17 to the arm 18 of the lever are spaced links 19 and 20, which links are in parallel relation to each other, and are held in parallel relation during a vehicle jacking or lowering position by means of the link 21, which has its ends pivoted at 22 to the upper ends of the spaced links 19 and 20, which link 21 in connection with the arm 18, causes a parallel movement of the links 19 and 20 when the same are extended in position shown in Figure 1 for raising an axle of the vehicle when the same is disposed in an axle engaging member 23 of the link 19. Disposed in parallel relation to the link 21, and to the arm 18 of the lever 14, is a link 24, which link is pivoted at 25 to the links 19 and 20, and at 26 within the bifurcation of the standard 5. The link 24, when the arm 15 of the lever 14 is forced downwardly, causes the upper end 27 of the link 20 to pass upwardly and rearwardly until its arm 28 is disposed above the upper end of the standard 5, at which time the pivoted dog 29 carried by the arm 28 will move upwardly in engagement with the rear faces 30 of the arms 31 of the standard 5 until it is forced into engagement with the notch 32 in the arms by the spring 33. When the detent 29 is in engagement with the notches 32, the link members will be held in extended positions as shown in Figure 1, thereby holding the vehicle axle or other object in raised position. When the pivoted dog 29 is forced inwardly under the influence of the spring 33, the nose thereof engages a spring 34 secured to the standard by means of the bolts 13. The spring 34 is 105 slightly weaker than the spring 33, therefore is bowed, and at the same time allows the pivoted dog 29 to move into engagement with the notches 32. However when it is desired to lower the device, the weighted cam 35 which is pivoted to one of the arms 31 at 110 36 is moved around in the direction of the

arrow *a* until it engages the spring 34. The weighted cam is of sufficient weight that when the dog 29 is raised slightly by downward pressure on the arm 15 of the lever 14, the combined force of the spring 34 and the weighted cam 35 will be greater than the power of the spring 33, thereby moving the free end of the dog 29 outwardly in the direction of the arrow *b* and consequently allowing the arm 15 to move upwardly and the axle engaging member 23 to move downwardly, thereby lowering the axle.

From the above it will be seen that a jack is provided wherein the lazy tong principle is used, and one wherein the operation is positive and the parts are reduced to a minimum.

The invention having been set forth what is claimed as new and useful is:—

- 20 1. A vehicle jack comprising a bifurcated standard, a lever pivoted in the bifurcation of said standard, a parallel link device carried by said lever and having one of its ends adapted to be forced upwardly upon a downward movement of the lever, an axle engaging element carried by the upwardly moved end, and a spring actuated dog carried by said link construction and cooperating with a notch in the standard for holding the link construction in extended position.
- 25 2. A vehicle jack comprising a standard, a lever pivoted to spaced arms carried by said standard, parallel disposed links spaced from each other and having their lower ends pivoted to one end of the pivoted lever, said links extending upwardly and connected to-

gether by a link, a second link pivoted between the arms of the standard and having pivotal connections with the first mentioned parallel links, the upper end of the outer parallel link having an axle engaging element, the upper end of the other parallel link having its end above its pivoted point extended and disposed above the upper end of the standard, a spring actuated dog pivoted to said extended end and positioned to cooperate with a notch in the standard and hold the links in extended position after a downward movement of the lever.

3. The combination with a pivoted dog carried by a vertically movable portion of a jack, the free end of said dog being formed into engagement with a notch in the jack standard for holding the jack in raised position, of a spring in the path of the free end of said dog and carried by the standard, said spring being weaker than the dog spring and flexed thereby, and a pivoted weighted cam carried by the standard and of sufficient weight when placed in engagement with the standard spring to overcome the tension of the dog spring and force the free end of the dog out of engagement with the notch in the standard.

In testimony whereof I have signed my name to this specification in the presence of two subscribing witnesses.

PETER IVARSEN NAMTVEDT.
